UNITED STATES PATENT OFFICE.

CARL G. OLSON AND NIKOLA TRBOJEVICH, OF CHICAGO, ILLINOIS, ASSIGNEES TO
ILLINOIS TOOL WORKS, OF CHICAGO, ILLINOIS, A CORPORATION OF ILLINOIS.

COMBINATION ROUGHING AND FINISHING HOB.

1,343,276.

Specification of Letters Patent. Patented June 15, 1920.

Application filed August 9, 1919. Serial No. 316,361.

To all whom it may concern:

Be it known that we, CARL G. OLSON, a citizen of the United States of America, and NIKOLA TRBOJEVICH, a subject of the King of Jugo-Slavia, both residing at Chicago, in the county of Cook and State of Illinois, have invented a certain new and useful Improvement in Combination Roughing and Finishing Hobs, of which the following is 10 a specification.

Our invention relates to hobs, and is particularly adapted for the production of worm wheels used in worm drives. It is of especial value in worm drives of a ratio approximating unity—that is, where the speed ratio is somewhere near one to one. The general object of the invention is to produce a hob capable of advantageously producing a worm gear of this type. A contributory object is to provide a hob which may accurately produce a great number of gears. A drive of this character in which the ratio is anywhere near one to one requires that the gear shall be accurately formed, and consequently, the hob which produces it must maintain its accuracy. In order to obtain the best results, the diameter of the hob should be approximately equal to the diameter of the worm gear, and one of the objects of our invention is to produce a hob which will maintain its proper diameter over a long period of time, thus promoting economy as well as accuracy.

In carrying out our invention, we have 35 produced a hob formed in two separable sections. One of these constitutes the roughing section and the other the finishing section. In the design shown, the roughing section is of considerable axial length, while the finishing section is practically a ring—that is, the axial length is comparatively short. In the roughing section the teeth are smaller than in the finishing section, and furthermore, the roughing section, when viewed in outline, is tapered, the forward end being of smaller diameter than the end which adjoins the finishing section. This appearance is due to the fact that at the forward end of the roughing section the teeth are not so high as at the rear end, although the root circle remains constant from one end of the roughing section to the other.

We accomplish our objects by the construction illustrated in the accompanying drawings, in which—

Figure 1 is an assembly view showing our compound hob mounted upon an arbor. In association with the hob there is shown in dotted lines the position of the work before it reaches the hob, and in full lines the position and appearance of the work after it has been fed past the hob.

Fig. 2 shows the parts of the hob separated on the arbor.

Fig. 3 shows the type of worm gear which our hob is adapted to produce. This is sometimes known as the "Hindley gear" or a worm gear having an hour glass shape.

Like numerals denote like parts throughout the several views.

In the form shown in the drawings, the hob consists of a roughing section 1 and a finishing section 2. The roughing section is somewhat smaller in diameter and the teeth thinner than in the finishing section. It is of considerable length axially, and while this dimension may be varied, it is desirable that the length shall be not much less than one-half of the diameter, and it may be somewhat more if desired. The teeth of the roughing section are tapered so that those at the forward end are thinner than at the rear end—that is, the end adjoining the finishing section. To accomplish this the producing lathe is geared up so as to advance the producing tool on one side somewhat less than the basic helical lead of the thread of the hob, and on the other side somewhat more than the basic helical lead of the thread of the hob. The included difference in the length of a hob of this variation in lead may amount to approximately from $1/64$ to $1/32$ of an inch, and this will make the front teeth correspondingly thinner than the rear teeth. The hob is also relieved in such manner that the height of the teeth at the forward end is less than at the rear end, thus causing the roughing section to present a slightly tapered or truncated conical appearance when viewed from the side. The root diameter is constant, the variation in this respect being simply in the height of the teeth. Thus the teeth are both shorter and thinner at the forward end of the hob and gradually increase in thickness

and height toward the rear end. At the rear end they are practically if not quite full size and height.

The finishing section 2, in the preferred 5 form, has simply a single row of teeth distributed circumferentially, the forward or cutting end being of full outline so as to produce a worm gear of accurate configuration. The individual teeth of the finishing 10 section are, however, relieved as in an ordinary hob.

The roughing section has a hub 5 on its larger or rear end which fits into a counter bore or socket 6 formed in the forward end 15 or face of the finishing section. By thus causing the parts to interfit they are enabled to rigidly maintain their proper axial alinement.

While the manner of mounting the sections of the hob may be varied somewhat an advantageous construction is illustrated in the drawings. In this form an arbor is employed, the portion 7 being of full diameter with a portion 8 of reduced diameter adjacent to it whereby an annular shoulder 9 is formed. The hob sections 1 and 2 fit slidingly over the portion 8 and so also does a spacing sleeve 10. A portion 12 of the arbor is still further reduced in diameter, this 30 portion being threaded to take a lock nut 13. When the parts are assembled as shown in Fig. 1, the hob sections 1 and 2 are held tight together between the shoulder 9 and sleeve 10, and the sleeve is held in position 35 by the nut 13. The portion 8 of the arbor is provided with a feather 14 by which the hob sections are splined to the arbor, and thus rigidly held against angular movement relatively to each other. It is important that 40 the hob sections should be accurately assembled, angularly, so that the helical sequence of the teeth of the two sections will be maintained. The splining of the parts on the arbor accomplishes this, care being required 45 in the manufacture of the hob to see that the keyways of the two sections are accurately positioned.

In practice, when the parts are assembled, as described and as shown in Fig. 1, the parts 50 are rotated and are fed in the manner typified by the arrows in said figure. Assuming that the roughing hob is placed toward the left, and the helical lead of the runs as illustrated, the top of the hob will rotate toward 55 the observer and the worm gear to be produced (indicated by the numeral 15) will rotate in a clockwise direction. The work will be fed toward the right or, if preferred, the hob may be fed toward the left, although the 60 former method is preferred in practice. The hob and the work are rotated in timed relation and after the work has traveled past the hob it will appear as shown in full line at the right end of Fig. 1. When viewed 65 from the side the finished work will appear

as shown in Fig. 3. According to the proportions illustrated, the work produced will be in the form of a Hindley or hour glass spiral worm gear adapted for a one to one speed ratio.

As a result of our invention it becomes possible to produce a worm gear of the type shown in a practical and commercial manner. The roughing hob section, as its name indicates, roughs out the work, but before 70 leaving it brings it to a state approaching final configuration. Consequently, the finishing section is called upon simply for bringing the configuration of the work to final, perfect form, and hence the wear upon 75 the finishing section is inconsiderable. This makes it possible to employ the finishing section for a large amount of work before re-sharpening is required. This is of great advantage because the finishing section requires 80 great care in manufacture and as it must maintain proper configuration within narrow limits in order to produce accurate pieces of work only a limited number of re-sharpenings are permissible. But with our 85 construction, the finishing section may be used a long time without resharpening, and when worn down to the lowest permissible limit a new finishing section may be substituted but the original roughing hob may 90 still be employed, thus enabling the user to 95 get maximum value out of the tool.

Having thus described our invention what we claim as new and desire to secure by Letters Patent, is:—

1. A compound hob having a plurality of individual separable sections, one constituting a roughing section and another, a finishing section, means for holding them in axial alinement, and means for locking them 105 in proper position angularly about the axis of rotation.

2. A hob consisting of a roughing section and a finishing section having helically arranged teeth, said sections being separable, 110 means for holding said sections side by side in axial alinement, and means for locking said sections relatively rigid with their teeth in proper angular sequence.

3. A hob having helically arranged teeth, 115 said hob having a roughing section and a finishing section, separable from each other, an arbor for supporting and rotating said sections, and means for locking said sections to the arbor with the teeth in proper helical 120 sequence.

4. A hob having teeth arranged helically, 125 said hob consisting of a finishing section and a roughing section helically in advance of the finishing section, and separable from it, an arbor adapted to support the sections side by side and rotate them, said sections having interfitting ends for adding to the rigidity with which the sections are held in axial alinement, and means for locking the 130

sections against relative rotation to thereby insure that the teeth shall be and remain in proper helical sequence.

5. A hob having a roughing section and a finishing section, the finishing section having a single row of teeth distributed circumferentially whereby all of the teeth of the work are finished at the same time.

6. A hob consisting of a roughing section 10 and a separate finishing section, the rough-

ing section having helically configurated teeth arranged helically, the roughing teeth being smaller than the finishing teeth and the finishing teeth being helically configurated but arranged in the form of a ring concentric 15 with the axis of the tool.

In witness whereof we have hereunto subscribed our names.

CARL G. OLSON.

NIKOLA TRBOJEVICH.
